UNITED STATES PATENT OFFICE.

JOSEPH L. STENGEL, OF MIDDLESBORO, KENTUCKY, ASSIGNOR TO MARTIN-PAGE COMPANY, OF MIDDLESBORO, KENTUCKY, A CORPORATION OF KENTUCKY.

ATHLETIC SUPPORTER.

Application filed May 23, 1925. Serial No. 32,395.

To all whom it may concern:

Be it known that JOSEPH L. STENGEL, a citizen of the United States, residing at Middlesboro, in the county of Bell and State 5 of Kentucky, has invented certain new and useful Improvements in Athletic Supporters, of which the following is a specification.

This invention relates to new and useful 10 improvements in athletic supporters generally, although from certain aspects the invention relates to flat seams employed in various garments.

Athletic supporters as heretofore constructed have been formed with lapped 15 seams which have necessitated one face only being positioned in direct contact with the wearer in order to avoid any chafing or rubbing which would otherwise occur should 20 the reverse side of the supporter be placed in direct contact with the wearer. Furthermore, in supporters heretofore constructed elastic webbing has been employed, but the seams connecting the various sections of the 25 webbing have not been constructed so as to retain the supporter in proper shape nor to prevent the cut ends of the sections from projecting through such seams.

One of the important objects of my invention is to provide a supporter in which 30 each of the seams thereof includes adjacent webbing sections disposed in edge abutting relation whereby the supporter may be readily reversed and either face thereof employed in direct contact with the wearer 35 without any chafing or rubbing action resulting therefrom.

Another important object of the invention 40 is to join two elastic web sections by a seam which is so constructed as to not only cover the severed ends of the webbing, but also anchor the rubber strands of the webbing whereby they will be retained in their normal positions whenever the webbing is 45 subjected to longitudinal expansion.

Another object of the invention lies in the provision of a flat seam of the character 50 described in which a reinforcing tape is secured along the cut edge portion of one of the webbing sections so as to prevent stretching of the webbing whereby said webbing will retain its original shape and whereby said tape will assume all strain

which would otherwise be directed to said 55 webbing.

With these and other objects in view 60 which will more readily appear as the nature of the invention is better understood, the same consists in the novel construction, combination and arrangement of parts hereinafter more fully described, illustrated and claimed.

In the accompanying drawings, 65 Figure 1 is a perspective view of an athletic supporter constructed in accordance 65 with my invention;

Figure 2 is a side elevation thereof, the 70 supporter being folded;

Figure 3 is an enlarged bottom plan view 75 showing the seams for uniting the pouch sections with the side straps;

Figure 4 is an enlarged plan view showing the seam and stitch construction thereof, which unites the pouch sections;

Figure 5 is an enlarged plan view showing 75 the seam connection between the waist band and the pouch;

Figure 6 is a sectional view showing dia- 80 grammatically the seam shown in Figure 5;

Figure 7 is a sectional view showing dia- 85 grammatically the seam connection between the waist band and the side strap;

Figure 8 is a sectional view showing dia- 85 grammatically the seam connection between the side straps and the pouch;

Figure 9 is a sectional view showing dia- 90 grammatically a modified form of seam structure;

Figure 10 is a similar view but showing 90 another modified form of seam structure;

Figure 11 is a sectional view showing dia- 95 grammatically the seam construction connecting the pouch sections, and

Figure 12 is a similar view but showing 95 diagrammatically the seam structure joining the adjacent ends of the waist bands.

Like reference numerals designate corre- 100 sponding parts throughout the several figures of the drawings.

Referring to the accompanying drawings, 100 A indicates an athletic supporter constructed in accordance with my invention. This supporter is preferably formed of elastic webbing sections and includes a waist band B, a pouch C, and side straps D.

The webbing sections are each formed of

woven cloth and include a plurality of rubber strands 5 which extend longitudinally thereof, the longitudinal edges being selvages. Thus each section is capable of longitudinal expansion but incapable of transverse expansion. It will therefore be understood that if a section is cut across at any angle less than 90 degrees, the cut edge is rendered capable of being expanded, and the smaller the degree of the cut the greater the amount of expansion can be obtained. It will also be understood that unless the severed end portions of the rubber strands are properly anchored, any longitudinal expansion of a section will serve to pull said end portions of the strands towards the center of the section, i. e., away from the cut edge of the section. The effect of this movement of the strands is to reduce the elastic efficiency of the section, to change the shape of the section, and to produce a wavy and therefore objectionable appearance to said section.

The waist band B is preferably formed from a single length of elastic webbing, the cut end portions being disposed in abutting relation and secured in such relation by a flat seam construction which I have indicated as a whole by the reference numerals 6.

The pouch C is formed from a pair of elastic webbing sections 7, 7 which are arranged side by side and secured in such relation by a flat seam 8. The lower portions of the sections 7 are cut on curves which extend downwardly and outwardly, each curve being formed by cutting the webbing across the rubber strands 5. These cut edges extend from the inner or meeting edges of the sections 7 downwardly and outwardly to the outer edges of the respective sections. The flat seam 8 is formed by covering the curved cut edges of the sections 7 by a line of covering stitches 9 which also secures a non-elastic tape 10 to the section in position along said cut edge, and then joining the meeting edges of the sections 7, 7 by a line of stitches 11.

The side straps D are likewise formed of elastic webbing and are preferably formed from a continuous strip of such webbing, said strip being folded intermediate its ends as shown in Figures 3 and 8, the folded edge being disposed in abutting relation relative to the lower rear edge of the pouch C so as to extend on opposite sides of the seam which joins the meeting edges of the pouch sections. A flat seam 12 unites the folded edge portions of the side straps D with the pouch C.

The upper edge portion of the pouch C is disposed in abutting relation with the lower edge portion of the waist band B, and is united thereto by a flat seam 13.

The upper edge portions of the side straps

D are likewise positioned in abutting relation with the lower edge portion of the waist band B and are joined thereto by flat seams 14, 14.

In forming the pouch C, the lower portions of the two sections 7 are each cut so as to present rounded lower edge portions. Each rounded edge portion extends across the rubber strands of the webbing and the cut edge portion of each section is fed through a sewing machine which lays covering threads over and around said cut edge portion. I preferably employ a sewing machine of the overlock type. Such a machine produces a line of stitches having a needle thread 15 and a looper thread 16, the needle thread 15 including a plurality of penetrant needle thread loops 15^a which enter the tape 10 and webbing section 7. Between adjacent needle loops the needle thread is formed into covering loops 15^b which extend laterally beyond and cover the cut edge of the section. The covering loops 15^b are concatenated along the cut edge with the covering loops 16^a formed by the looper thread 16, the looper thread loops being in turn concatenated with the needle thread loops on the outer face of the tape. Thus the penetrant needle thread loops serve to anchor the rubber strands of the webbing against bodily movement when the webbing is expanded longitudinally, and by reason of these needle thread loops and the looper thread loops extending over the cut edge, the frayed ends of the woven cloth and the adjacent ends of the rubber strands are covered and are thereby held against working outwardly beyond the plane of either face of the section 7. After the cut edges of the sections 7 are thus covered, I position the meeting edges thereof in abutting relation and then join said sections by the line of stitches 11 which as shown are produced by a zig-zag sewing machine. Thus a line of zig-zag stitches is formed consisting of a needle thread 17 and a lower or looper thread 18. The needle thread 17 is formed into a connected line of staggered needle thread loops which alternately penetrate both tapes 10 and adjacent portions of the fabric sections 7. This line of stitches 11 is continued beyond the cut edges of the sections so as to also secure the upper meeting edges of said sections 7, 7 in abutting relation.

By thus curving the lower portions of the meeting edges of the pouch sections 7 and then joining said section by the seam 8, I have properly shaped the bottom portion of said pouch and by employing the tapes 10 along said cut edges I have reinforced the same whereby the shape of the pouch will be maintained and whereby all strain will be imposed on said tape and consequently stretching of the sections lengthwise of the cut edges will be prevented.

The seam 12, which unites the side straps D with the pouch C, is preferably formed by a zig-zag sewing machine by which a line of staggered needle thread loops is formed, the alternate loops penetrating the straps D, D and the pouch C, as shown diagrammatically in Figure 8.

The upper edge portion of the pouch C is then joined to the lower edge of the waist band B through the medium of the seam 13. This seam 13 is shown in Figures 5 and 6. The upper cut edge portions of the sections 7 are first covered by a line of overlock stitches 18, the needle thread loops 19 thereupon of penetrating the tape 20 and pouch sections 7. The needle thread loops 19 extend over the cut edges and concatenate with looper thread loops 21. A line of zig-zag stitches 22 unites the upper portion of the pouch 20 with the lower portion of the waist band. Thus the needle thread loops 19 securely anchor the end portions of the rubber strands 5 of the pouch sections 7 against bodily movement when the sections 7 are expanded longitudinally.

Each of the seams 14, which form the connections between the ends of the said straps B and the waist band, is similarly formed as shown in Figure 7. In this figure the tape 30 is indicated at 23, the overlock stitches at 24, and the zig-zag stitches at 25.

The cut ends of the waist band B are then united by the seam 6 which is diagrammatically shown in Figure 12, the construction 35 of this seam being identical with that shown in Figure 11. This seam 6 includes the meeting end portions 26, 26 of the waist band B, the cut edges thereof being disposed in abutting relation. Each edge portion is covered by a line of overlock stitches which I have indicated as a whole by the reference numeral 27, each line of said stitches securing a tape 28 along the adjacent cut edge. These abutting cut edge portions are then 45 united by a line of zig-zag stitches 29.

Another advantage is obtained by employing the tapes along the cut edges of the elastic webbing, viz., it serves to form a better holding means for the needle thread loops 50 which penetrate said tapes and therefore permits of very short stitches to be employed. The employment of short stitches is decidedly advantageous in that the cut edge portions are better covered.

I may desire to employ covering stitches for the cut edges of the webbing, of a type known as triple interlock stitches, as diagrammatically shown in Figure 9. Triple interlock stitches are formed by a sewing 60 machine which includes three needles and a single threaded looper cooperating therewith. This machine produces three lines of connected needle thread loops 30, 31 and 32, respectively, a lower covering thread 33 which concatenates with all of said needle

thread loops and one or more upper covering threads 34. The needle thread loops 30 will cover the cut edge of the fabric, whereas the needle loops 31 and 32 will penetrate the tape 35 and webbing 36.

It may, however, be desired to further increase the holding or retaining qualities of the overlock covering stitches and to this end I have provided the seam with a separate line of straightaway stitches 37, as shown in Figure 10. In this form I have indicated the overlock stitches as a whole by the numeral 38, the tape by the numeral 39, and the webbing by the numeral 40. The line of straightaway stitches 37 includes a series of connected needle thread loops which penetrate the tape 39 and webbing 40. This needle thread also serves to tie down the looper thread loops and the needle thread loops of the overlock stitches 38 and also serves to more securely retain the ends of the rubber strands against longitudinal movement when the webbing is subjected to longitudinal expansion.

From the foregoing it will be seen that I have provided an athletic supporter in which all parts are connected by flat seams, thus permitting either face of the supporter being worn directly against the wearer, and also forming a resultant supporter which is readily reversible; that I have reinforced the cut edges of the elastic webbing so that strains transverse to the rubber strands will be taken up by the tapes which form inherent parts of the seams; that the cut edges are properly covered so as to prevent the cut end portions of the webbing from projecting beyond either face of the webbing, and that the rubber strands are securely anchored against bodily movement whenever the webbing is subjected to longitudinal expansion.

Having thus described my invention what I claim as new is:

1. In an athletic supporter, a pouch including in combination two longitudinally elastic webbing sections disposed in abutting relation and having cut edges extending across the sections, a line of stitches secured to each section and covering cut edges thereof and engaging and anchoring the elastic parts of the webbing, and a line of stitches connecting said sections and including anchored needle thread loops extending through the respective sections.

2. In an athletic supporter, a pouch including in combination two longitudinally elastic webbing sections disposed in abutting relation and having cut edges extending across the sections, a line of stitches secured to each section and covering cut edges thereof and engaging and anchoring the elastic parts of the webbing, and a line of stitches connecting said sections and including anchored needle thread loops extending

through the respective sections, said connecting stitches being confined within the borders of the covering stitches.

3. In an athletic supporter, a pouch including in combination two longitudinally elastic webbing sections disposed in abutting relation and having cut edges extending across the sections, a line of stitches secured to each section and covering cut edges thereof and engaging and anchoring the elastic parts of the webbing, an inelastic tape secured by said covering stitches to one face of each section along the cut edge thereof, and a line of stitches connecting said sections and including anchored needle thread loops extending through the respective sections and tapes.

4. In an athletic supporter, the combination of a waist band, and a pouch, said pouch including a longitudinally elastic webbing section having a cut edge extending across the section and disposed in abutting relation to one edge of said waist band, a line of stitches secured to said webbing section and covering the cut edges thereof and engaging and anchoring the elastic parts of the webbing, and a line of stitches connecting said waist band and webbing section and including anchored needle thread loops extending through said band and section on opposite sides of said abutting edges.

5. In an athletic supporter, the combination of a waist band, and a pouch, said pouch comprising two longitudinally elastic webbing sections arranged side by side and having upper cut edges disposed in abutting relation against the lower edge of the waist band, the meeting edges of the sections throughout the length of the pouch being connected by a line of stitching, a line of stitches covering the cut edges of the pouch sections and engaging and anchoring the elastic parts of the webbing, an inelastic tape secured by said covering stitches to one face of said sections and extending across the meeting edges thereof, and a line of stitches connecting said waist band and pouch sections and including anchored needle thread loops extending through said band and sections and tape on opposite sides of said abutting edges.

6. In an athletic supporter, the combination of a waist band, and a pouch, said pouch comprising two longitudinally elastic webbing sections arranged side by side and having upper cut edges disposed in abutting relation against the lower edge of the waist band, the meeting edges of the sections

throughout the length of the pouch being connected by a line of stitching, a line of stitches covering the cut edges of the pouch sections and engaging and anchoring the elastic parts of the webbing, an inelastic tape secured by said covering stitches to one face of said sections and extending across the meeting edges thereof, the lower portions of said sections having their meeting edges curved from the inner longitudinal edges of the sections to the outer longitudinal edges thereof, and side straps connecting the waist band and the bottom of the pouch along the outer longitudinal edges of the sections and extending on opposite sides of their meeting edges.

7. In a reversible athletic supporter formed from cut sections of elastic webbing, the combination with a waist band, sections of a pouch having its upper cut edge disposed in abutting relation to the lower edges of the band and stitched thereto, side straps connecting the waist band and pouch, the upper cut ends of the straps being disposed in abutting relation to the lower edge of the waist band and connected thereto, the lower ends of the straps being disposed in abutting relation to the lower edge of the pouch, and separate lines of stitches respectively extending transversely of certain of the sections adjacent the cut ends thereof to anchor the elastic parts of said sections. 90

8. In a reversible athletic supporter formed from cut sections of elastic webbing, the combination with a waist band section having its cut ends disposed in abutting relation and joined by a line of stitches, of a separate line of stitches extending transversely of the waist band adjacent each cut end thereof to anchor the elastic parts of the webbing, a pouch having its upper cut edge disposed in abutting relation to the lower edge of the band and stitched thereto, a separate line of stitches extending transversely of the pouch adjacent the cut edges thereof to anchor the elastic parts of the webbing forming the pouch, side straps connecting the waist band and pouch, the upper cut ends of the straps being disposed in abutting relation to the lower edge of the waist band and stitched thereto, and a separate line of stitches extending transversely of each strap adjacent the cut end thereof to anchor the elastic parts of the webbing forming the strap. 105 110

In testimony whereof I hereunto affix my signature.

JOSEPH L. STENGEL.
